(57) **CLAIM**

I claim the ornamental design for an air compressor accessory package, as shown.

DESCRIPTION

FIG. 1 is an isometric view of the air compressor accessory package showing my new design;

FIG. 2 is a top plan view thereof;

FIG. 3 is a left side elevation view thereof;

FIG. 4 is front elevation view thereof;

FIG. 5 is a right side elevation view thereof;

FIG. 6 is a rear elevation view thereof; and,

FIG. 7 is a bottom plan view thereof.

The broken line portions of the disclosure are for illustrative purposes only and form no part of the claimed design.
